UNITED STATES PATENT OFFICE.

GEORG LARSEN, OF BROOKLYN, NEW YORK.

ADJUSTABLE MOLDING STRIP.

Application filed July 14, 1927. Serial No. 205,587.

The main object of this invention is to provide a molding strip which may be used on windows or doors and its construction is such that it will permit transverse shifting 5 of the strip to permit it to be adjusted to various positions to take up for space which would occur when the molding strip shrinks or is otherwise deformed.

Another object of this invention is to provide 10 a molding strip which is adjustably mounted upon the frame of a window or door and is transversely movable across the frame of the window or door for the purpose of compensating for shrinkage, warpage and 15 other defects common in the usage of such doors and windows.

The above and other objects will become apparent in the description below in which characters of reference refer to like-named 20 parts in the drawing.

Referring briefly to the drawing, Figure 1 is a perspective view of a portion of a door or window frame showing the adjustable molding strip mounted in place thereon.

Figure 2 is a front elevational view of a 25 section of a door or window frame showing the molding strip, partly broken away at one portion, mounted thereon.

Figure 3 is a side elevational view of Figure 2 showing a portion of the molding strip and frame broken away to illustrate the construction thereof.

Figure 4 is a cross sectional view taken on line 4-4 of Figure 3.

Figure 5 is a perspective view of the bolt used with the adjustable molding strip.

Referring in detail to the drawing, the numeral 10 indicates the upright board on one side of a door or window and forms part 40 of the frame of the door or window. At spaced apart positions on this board, a plurality of straight slots 11 are formed. These slots extend transversely across said board and are adapted to be entirely concealed by the molding strip 12. The frame of the door or window is preferably of hollow construction and the slots 11 in the board are adapted to receive securely bolts. These bolts comprise a shank 13 circular in cross section and threaded at one 45 end as indicated by the numeral 14. The end of the bolt opposite to the threaded end is provided with a square head 15 and is surmounted by ledges 16 which project in opposite directions from the top of the square head. The distance between the flats of the

square head is slightly less than the width of the slot 11 formed in the frame board 10 and the widths of the ledges 16 are of the same dimension, while the distance between 60 the edge of one ledge to the edge of the opposite ledge is slightly less than the length of the slot 11, so that the ledge and square end of the bolt may be passed through the slot 11 from one side of the board. The 65 threaded ends of the bolts are adapted to project outwardly from the face of the board 10 and serve as anchors for the molding strips 12.

The molding strip 12 may be of continuous 70 length or of shorter lengths arranged end to end in a butt or lap joint. The molding strips are of hollow construction being provided with an inner concealed channel 17 which is surrounded by side walls 18 and 19 75 and a roof 20, the remaining side being opened. Secured in the channels, at distances spaced apart from each other equal to distances between the slots 11, blocks 21 are located. These blocks are securely fixed 80 to the walls and roof of the molding strip through any desirable means and are provided with openings. These openings pass thru the blocks and the roof 20 of the molding strip and receive the threaded ends 13 85 of the bolts. The exposed face of the roof 20 has conical seats which surround the openings, receiving the bolts and has conical threaded washers 22 seated thereon, the washers engaging the threaded ends of the 90 bolts.

The molding strip illustrated herein is adapted to compensate or take up for whatever shrinkage occurs in the building materials used, which is ordinarily wood. If 95 a space between molding strips and doors were to be created thru shrinkage or warpage an unnecessary strain would occur on the hinges of the door and in the case of windows the same would not be weatherproof and would rattle in the wind. To eliminate the necessity of pulling nails or screws from a permanently mounted molding strip to shift the same, this invention has been conceived. The bolt is slidable in the 100 slot and after slightly loosening the threaded washers 22 the entire molding strip may be shifted transversely the length of the slot 11 from one side to the other. Only slight shifting of the molding strips is necessary 110 as the degree of shrinkage or warpage of the said strips is never great. After the

molding strip has been shifted to its new position the washer 22 is again tightened thereby releasably securing said molding strip in place in its new position on the 5 frame or end of the door or window.

It is to be noted that certain changes in form and construction may be made without departing from the spirit and scope of the invention.

10 I claim:

1. In combination with a frame board of a door or window said board having spaced apart slots therein extending transversely a channel molding strip covering said slots, 15 blocks secured within said molding strips, bolts slideable and non-rotatable in said slots engaging the molding strips for anchoring the same and means engaging said bolts for securing said molding strips adjustably in 20 position within the limits of said slots.

2. In combination with a frame board of a door or window said board having spaced apart slots therein extending transversely, a channel molding strip covering said slots, 25 blocks secured within said molding strips,

bolts slideable and non-rotatable in said slots engaging the molding strips for anchoring the same, a conical washer engaging said bolt, said washer when tightened on said bolt releasably securing the molding strip 30 in any desired position.

3. In combination with a frame board of a door or window said board having spaced apart slots therein extending transversely, 35 a channel molding strip covering said slots, blocks secured within said molding strips, bolts slideable and non-rotatable in said slots engaging the molding strips for anchoring the same, a conical washer engaging said bolt, said washer when tightened on said 40 bolt releasably securing the molding strip in any desired position, said bolt having a circular threaded shank, a square head on said shank and ledges surmounting said square head, the ledges forming a stop shoulder and the square head permitting 45 sliding of the bolt in said slots but non-rotatable thereof.

In testimony whereof I affix my signature.

GEORG LARSEN.
